To all whom it may concern:

Be it known that we, N. G. Becker and William L. The description of our stove design is as follows, viz; The top plate is of an oval form, and decorated upon its surface with the shell work bordering (a) in two apertures (b); (c) is a center piece of shell work, and having a mottled border (d). The bottom plate is ornamented in front with a shell (e) and shell rosettes (f) at each corner, and between them is arranged scalloped shell work (g). The rim plate has a shell work top (h) ornamental handles (i), bowl and base (j) and (k). The end plate and door are decorated thus; the door (l) has a scalloped shell work border (m) and center piece (n); and the end plate has the ornamental bordering (o) around its edges. The register plate has the shells (p, p) and scalloped border (q); the leg is decorated on its face with the shell (r) and bow (s).
